UNITED STATES PATENT OFFICE.

WALTER H. FAIRCHILD, OF EVANSTON, ILLINOIS, ASSIGNOR TO MID-WEST BOX COMPANY, OF ANDERSON, NEW YORK, A CORPORATION OF INDIANA.

INCANDESCENT-LAMP WRAPPER.

Application filed April 18, 1918. Serial No. 229,225.

To all whom it may concern:

Be it known that I, WALTER H. FAIRCHILD, a citizen of the United States, and a resident of Evanston, in the county of Cook and State of Illinois, have invented certain new and useful Improvements in Incandescent-Lamp Wrappers, of which the following is a full, clear, and exact description.

The invention relates to wrappers which are more particularly adapted to contain an electric incandescent lamp so that it will be protected against breakage.

It is now common practice to employ tubular wrappers which are formed of longitudinally corrugated straw board. In these wrappers, the resiliency of the longitudinal corrugated tubular container has been relied upon to exert pressure against the portion of the lamp bulb having the greatest diameter, to hold the lamp and the wrapper against relative longitudinal displacement to keep the lamp protected by the wrapper. In practice, it has been found that this resiliency alone cannot always be relied upon to hold the lamp in the carrier and one object of the present invention is to provide an improved wrapper in which provision is made for restricting the margin of the wrapper disposed adjacent the glass tip on the bulb so that that margin will be measurably held against expansion by the bulb and to more securely keep the lamp in the wrapper.

A further object of the invention is to provide an improved construction and method whereby independently formed tubular wrappers will be connected together for convenience in handling or loading them.

The invention consists in the several novel features hereinafter set forth and more particularly defined by claims at the conclusion hereof.

In the drawings: Fig. 1 is a perspective of a connected series of wrappers embodying the invention, a lamp being illustrated in one of them. Fig. 2 is an inverted end view of one of the wrappers with a lamp therein.

The invention is illustrated as embodied in a series of wrappers, each of which is formed of a strip of straw board which is longitudinally corrugated, as at 3, and has its ends lapped and secured together, as at 4, to form a tube or complete tubular wrapper. The upper and lower ends of the wrapper

are open and the straw-board, which is the material usually used, is somewhat resilient so that by reason of the longitudinal corrugations the tubular wrapper can be expanded, as at 6, by the widest portion of the bulb of an incandescent lamp 7. It is desirable to restrict the tubular wrapper to prevent the lamp from being pushed downwardly through the wrapper so far that the glass tip, usually present on the bulb, will be unprotected and for this purpose corrugated strips of paper 8 and 9 are secured to the outside of the lower margin of each tubular wrapper, the inner faces of these strips preferably secured by a suitable agglutinant to the wrapper.

In packing lamps in these tubular wrappers, it has been found that the work may be expedited by feeding the wrappers in connected series to a packer or a packing machine. The corrugated tubes are first independently or individually formed and for the purpose of temporarily securing the wrappers together serially, the strips 8 and 9 are applied to the wrappers from long strips or webs and are continuously secured on the lower margin of the sides of the wrapper respectively. When the wrappers have been loaded, the continuous strips 8 and 9 can be easily severed between the tubes, so that the wrappers can be individually handled.

The invention exemplifies a wrapper which is individually formed of corrugated paper and is provided at one margin with a strip or strips fixed thereto to restrict the expansion of that margin relatively to that portion of the wrapper designed to hold the widest portion of the lamp. Also one in which the tubular corrugated wrappers are individually formed and are serially connected by means of strips which are utilized to restrict the expansion of one marginal portion of the wrapper, the other marginal portion being unrestricted so that the lamp can be inserted into it.

Whilst the invention has been designated a lamp wrapper, it will be understood that it is usable for other articles and more particularly in wrappers for articles which have portions of different sizes, so that expandable and restricted portions are necessary.

The invention is not to be understood as restricted to the details set forth, since these

may be modified within the scope of the appended claims, without departing from the spirit and scope of the invention.

Having thus described the invention, what I claim as new and desire to secure by Letters Patent, is:

1. Incandescent lamp wrappers comprising a series of independently formed longitudinally corrugated resilient tubes and a severable continuous comparatively narrow strip secured to one portion of said tubes to temporarily hold them together serially and

to restrict the expansion of one end of each tube by the lamp bulbs.

2. Incandescent lamp wrappers comprising a series of independently formed longitudinally corrugated resilient tubes and continuous strips of paper secured to opposite sides of one portion of said tubes to temporarily hold them together serially and to restrict the expansion of one end of each tube by the lamp bulbs.

WALTER H. FAIRCHILD.
